US0D1054022S

(12) **United States Design Patent** (10) **Patent No.:** **US D1,054,022 S**
(45) **Date of Patent:** **** Dec. 10, 2024**

(54) **MICRO-DOSING DEVICE**

(71) Applicant: **SHL MEDICAL AG**, Zug (CH)

(72) Inventors: **Thomas Burkard**, Baden (CH); **Fabian Bernhard**, Stetten (CH)

(73) Assignee: **SFL Medical AG**, Zug (CH)

(**) Term: **15 Years**

(21) Appl. No.: **29/892,415**

(22) Filed: **May 17, 2023**

Related U.S. Application Data

(63) Continuation of application No. 29/884,294, filed on Feb. 9, 2023, now Pat. No. Des. 997,350, which is a continuation of application No. 29/770,958, filed on Feb. 18, 2021, now Pat. No. Des. 980,975.

(57) **CLAIM**

The ornamental design for a micro-dosing device, as shown and described.

DESCRIPTION

FIG. 1 is a front, right, and above perspective view of a micro-dosing device;

FIG. 2 is a back, left, and below perspective view thereof;

FIG. 3 is a back elevation view thereof;

FIG. 4 is a front elevation view thereof;

FIG. 5 is a left side elevation view thereof;

FIG. 6 is a right side elevation thereof;

FIG. 7 a top plan view thereof; and,

FIG. 8 is a bottom plan view thereof.

The broken lines in the drawings illustrate portions of the micro-dosing device and form no part of the claimed design.

1 Claim, 8 Drawing Sheets
